UNITED STATES PATENT OFFICE.

BENEDICT F. PIOLA, OF SAN JOSE, CALIFORNIA.

DOG SHIELD.

Application filed March 9, 1926. Serial No. 93,484.

My invention relates particularly to a shield for dogs adapted to be mounted upon the running board of an automobile.

It is one object of the invention to provide a shield of the character indicated so formed and constructed as to be readily mounted upon the running board of an automobile and effectually protect the dog tethered therein against the wind.

10 It is another object of the invention to provide a device of the character indicated wherein the dog is effectually prevented from falling off from the running board or turning around thereon, and wherein the 15 vision of the dog is largely unobstructed.

It is also an object of the invention to provide a structure of the character indicated provided with an easily replaceable window.

Finally it is an object of the invention to 20 provide a structure of the character indicated that will be economical to manufacture, simple in form and construction, and highly efficient in its practical application.

In the drawing:—

25 Figure 1 is a side elevation of the device in an operative position on the running board of an automobile.

Figure 2 is an enlarged plan view of the same.

30 Figure 3 is a front elevation of the structure shown in Figure 2.

Figure 4 is a section on line 4—4 of Figure 2.

Referring more particularly to the drawing, I show at 1 a base board or plate, oblong in form and preferably having a squared end 2 and a rounded end 3 and adapted to be so positioned on the running board 4 of an automobile 5 that the parts 40 mounted thereon will in no way interfere with the opening of the doors of the automobile. In the form of the invention herein disclosed the rounded end of the base part 1 is placed against one of the forward fenders.

45 The base plate 1 is preferably made of substantially the same width as the running board 4 and has an orifice 6 formed therein through which a bolt 7 may be inserted to bolt the same to the said running board.

50 At 8 I show a sheet of metal mounted upon the front and side edges of the plate

1 its two ends terminating at the square end 2. This metal sheet is of any suitable height in front and preferably terminates in rounded ends as shown. Upon the top of the central portion of the sheet 8 is mounted a hood or deflector 9.

An opening 10 is formed in the front of the metal sheet 8 at a suitable height from its lower edge, and this opening has metal strips 11—11 positioned around both ends thereof as clearly shown in Figure 3, there being spaces 12—12 left between the opposing ends of the said strips, and the strips forming channels 13—13. In the channels 13—13 is slipped a transparent sheet of celluloid or other suitable material to form a window.

When the device is in use it is securely bolted to the running board as shown in Figure 1 with the window directed forwardly, and the dog is fastened by means of a chain to an eye 15 securely mounted in the device in any suitable position.

The window permits the dog to see forwardly when standing or sitting when the machine is in motion and yet it is effectually protected from the wind. The hood 9 serves to deflect the wind upwardly and beyond the dog's head. The high sides of the structure not only protect the dog from the elements, but also prevents it from being thrown to the ground when the machine turns a corner at some speed. These side portions also prevent the dog from turning around so that when the dog is once secured in position the owner may know that it is always safe and in its proper position.

The construction of the device permits of the arranging of suitable buttons as 16 around its edges so that a canvas, not shown, may be mounted thereon when desired to enclose the upper portion of the device and form a cover therefor.

By constructing the window as described, 95 the flexible window element 15 may be inserted by bending at the center and slipping the ends into the channels 13. It is readily removed and replaced by a new sheet without providing any movable parts to the 100 frame.

It is to be understood, of course, that while

I have herein shown and described but one specific embodiment of the invention, changes in form, construction and method of mounting may be made within the scope 5 of the appended claim.

I claim:—

A device of the character described comprising a base member with converging edges at one end and means for securing the same

upon the running board of an automobile, an 10 upstanding wall rising from the sides and converging edges and having a window mounted therein, a hood mounted on said wall and extending inwardly above said window, and a fastening element mounted on 15 said device.

BENEDICT F. PIOLA.
